MULTIPLE TRANSMITTER UNITS

Donald L. Hings, Ottawa, Ontario, Canada

Application May 3, 1944, Serial No. 533,860
In Canada April 25, 1944

7 Claims. (Cl. 250—17)

1

My invention relates in general to radio transmitting systems and more particularly to individual transmitting units which may be readily and easily combined or plugged together to give added power as well as give additional frequency channels.

An object of my invention is to provide for selectively operating one or a plurality of amplifying circuits from a single oscillator.

Another object of my invention is to provide for reducing the number of switch contacts and the shielding normally required between input and output circuits for channel frequency changing.

Another object of my invention is to provide for connecting the cathode of the selected oscillator tube in series with the cathodes of one or of the plurality of amplifier tubes for direct current and for exciting the cathodes of the amplifier tubes at radio frequency potential above ground.

Another object of my invention is to provide for energizing the cathodes of the amplifier tubes at radio frequency from the output oscillatory circuit of the selected oscillator.

Another object of my invention is to provide for switching the cathodes on the input side of the amplifiers instead of switching the grids.

Another object of my invention is to provide in one switch having a number of contacts for switching both the input side of the amplifier as well as the output side of the amplifier and at the same time prevent electrical inter-action which if allowed to occur may cause self oscillation.

Another object of my invention is to arrange for controlling the switching units at a remote point.

Another object of my invention is to provide for mounting a single transmitting unit in a single case having plug connections whereby one or a plurality of individual units may be readily replaced in case of failure of one or more of the operating units.

Other objects and a fuller understanding of my invention may be had by referring to the following description and claims taken in conjunction with the drawing in which the single figure represents a system employing three separate and individual units designated by the reference characters A, B and C. Although I have shown three individual and separate units it is to be understood that any larger number of units may be employed and still be within the scope of my invention.

2

The circuits for the three individual units A, B and C are substantially alike and where possible the corresponding parts are designated by the same reference characters.

In the unit A, the oscillator tube is designated by the reference character 10, in unit B by the reference character 11 and in unit C by the reference character 12. In unit A, the amplifier tube is designated by the reference character 20, in unit B by the reference character 21 and in unit C by the reference character 22. The transfer switch in unit A is designated by the reference character 40, in unit B by the reference character 41 and in unit C by the reference character 42. The cathodes for the oscillator tubes are designated by the reference character 13 and the inductance element of the output oscillatory circuit for each of the oscillator tubes is designated by the reference character 14. The inductance element of the output oscillatory circuits for the amplifier tubes are designated by the reference character 15. The plates 16 of all the amplifier tubes are arranged to be connected to the plate end of the selected oscillatory output circuit 15 through the selected switch contacts 33. Thus, for example, with the switch 40 closed, all the plates 16 are connected to the oscillatory output circuit 15 for the unit A. When B is the selected unit, all of the plates are connected to the oscillatory circuit for unit B. The same is true for unit C when it is selected. The aerial or antenna end of the oscillatory circuits 15 are arranged to be connected to the antenna 29 through a common conductor 45 and the switch contact 34 of the selected switch. The plates 16 are connected through a radio frequency choke 46 to high tension positive direct current potentials. The grids 17 of the amplifier tubes are by-passed to ground for radio frequency through capacitors 31. Each of the control grids 17 are connected to a common conductor 47 which is in turn connected to a suitable source of bias and modulation indicated by the reference character 19. All of the filaments 18 of the amplifier tubes and the filament 13 of the selected oscillator tube are connected in series for direct current excitation. With the switch 40 closed as shown in the drawing the direct current excitation for the cathodes may be traced from the low tension positive direct current potential in the lower right hand corner of the drawing through a resistance 48, a radio frequency choke coil 49, a switch 50, the filament 18 of the tube 22, the filament 18 of the tube 21, the filament 18 of the tube 20, the switch contact 32 to the tap 51 on the inductance coil 14 for the

oscillatory output circuit of the oscillator 10, and then through the filament 13 for the oscillator tube 10 to the negative side of the low tension direct current source. When the switch 41 is closed, the filament 13 for the tube 11 is connected in series with all the cathodes 18 of the amplifier tubes and when the switch 42 is closed the filament 13 for the tube 12 is connected in series with all the cathodes 18 of the amplifier tubes. The filaments 18 for all the amplifier tubes are energized at radio frequency potentials above ground through the adjustable tap 51 of the selected oscillator circuit. When the unit C is removed the switch 50 is closed for the unit B to complete the circuit for energizing the cathodes 18 of the units A and B. When both the units B and C are disconnected the switch 50 for the unit A is closed for completing the cathode circuit for the tubes of the unit A. The conductors passing between the terminals of the respective units may be in the form of male and female plugs as illustrated, so that the units may be readily removed and replaced to meet the requirements of the installation.

The transfer switches 40, 41 and 42 are selectively and individually controlled by a selector switch 68 having a rotating contact member 61 which selects the respective contact that leads to the energizing coils of the respective transfer switches. The selected transfer switch is not energized until the carrier switch 62 is depressed. The depression of the carrier switch 62 closes a circuit for energizing the selected coil from the illustrated low tension direct current source. The switch 62 is depressed to talk and modulate the carrier wave and the opening of the switch renders the transmitter inoperative.

The transfer switches 40, 41 and 42 interrupt the cathode circuits which are of low impedance and at the same time interrupt the output circuit of the amplifying tubes, and inasmuch as the cathode circuits are of a relatively low impedance with respect to ground, I am able to minimize the electrical inter-action between the input and output circuits which may tend to cause self-excited oscillations. In my circuit arrangements the switches require no shielding between their respective parts.

In operation, when the switch 40 is closed the oscillator tube A for the unit A is arranged to control the three amplifying tubes for the units A, B and C. When the oscillator for the unit B is selected it provides for controlling the amplifying tubes for the three units A, B and C, and when the oscillator for unit C is selected it provides for controlling the operation of the amplifiers for the three units A, B and C. The three amplifiers when in operation feed their power additively to the antenna 29. In actual practice the power of an installation may be increased merely by adding an additional unit which is a low cost method of increasing the power of an established station without rebuilding it for greater power output. The oscillators A, B and C are selected to oscillate at different frequencies although it is within the scope of my invention to have at least two of the units to operate at the same frequency so that in case one of the units fail the other unit may be locally or remotely switched into operation.

An example of the flexibility of adding power to an established installation may be had by referring further to the diagram.

It is understood that the common modulator unit used in conjunction with the excitor amplifier sections described may be of similar dimen-

sions and mounted in the same rack assembly. The power supply unit may be of like dimensions and where desirable may be mounted likewise.

Upon adding additional amplifier sections, the unit feed bus lines are carried through each unit chassis to plug terminals in such a way that the output amplifier tube terminals of all units are in series or parallel, regardless of which output circuit inductance is connected into the system or which excitor tube is driving the common cathodes.

In this manner, upon the addition of an amplifier unit, for an increased overall power output, it is necessary only to make minor realignment of the variable adjustment elements provided within those sections previously in use.

The inherent capacity of the modulator section and power supply normally would be of ample value to supply anticipated additional amplifier units. However, should this anticipated number be exceeded, then the power and modulator units would be increased in capacity as necessary.

Although I have shown and described my invention with a certain degree of particularity, it is understood that changes may be made therein without departing from the spirit of the invention which are included within the scope of claims hereinafter set forth.

I claim as my invention:

1. A radio frequency transmitting system, comprising a plurality of transmitter units each comprising an oscillator and an amplifier, plug connectors for connecting the units together, and transfer switching means for connecting a selected oscillator of any one of the units with all of the amplifiers of the units, an antenna; and circuit means for connecting the amplifiers to the antenna.

2. A radio frequency transmitting system, comprising a plurality of transmitter units each comprising an oscillator and an amplifier, plug connectors for connecting the units together, and transfer switching means for connecting a selected oscillator of any one of the units with all of the amplifiers of the units, an antenna, and circuit means for connecting the amplifiers to the antenna, each said oscillator having a tube including a cathode and an output radio frequency circuit, each said amplifier including an amplifying tube having a cathode, said transfer switching means connecting the cathode of the selected oscillator in series with all the cathodes of the amplifying tubes said cathodes of the amplifying tube being energized at radio frequency potentials from the output radio frequency circuit of the selected oscillator.

3. A radio frequency transmitting system comprising a plurality of transmitter units each comprising an oscillator and an amplifier, each said amplifier including a plate and an oscillatory output circuit, and transfer switching means for connecting a selected oscillator of any one of the units with all of the amplifiers of the units, an antenna, said switching means connecting the oscillatory output circuit of the selected unit with the antenna and with all of the plates of the amplifiers.

4. A radio frequency transmitting system comprising a plurality of transmitter units each comprising an oscillator and an amplifier, each said amplifier including a plate and an oscillatory output circuit, and transfer switching means for connecting a selected oscillator of any one of the units with all of the amplifiers of the units, an antenna, said switching means connecting the

oscillatory output circuit of the selected unit with the antenna and with all of the plates of the amplifiers, and means for controlling the switching means at a remote point.

5. A radio frequency transmitting system comprising an antenna, a plurality of transmitter units each comprising an oscillator circuit, an amplifier circuit and an output circuit, each said oscillator circuit including at least an anode electrode and a cathode electrode operating as space discharge means, means for connecting the cathode electrode of each oscillator circuit to a point of reference potential, each said amplifier circuit including at least a cathode element and an anode element operating as space discharge means, first switch means for connecting the anode electrode of the oscillator circuit of a selected one of said units with the cathode electrodes of the amplifier circuits of all of said units and thereby exciting the said cathodes at radio frequency potential above said reference point, and second switch means for connecting the anode electrodes of the amplifier circuit of all of said units in circuit relation with the output circuit of said selected one of said units and the antenna and thereby exciting the output circuit of said selected one of said units and the antenna from all of said amplifier circuits.

6. A radio frequency transmitting system comprising an antenna, a plurality of transmitter units each comprising an oscillator circuit, an amplifier circuit and an output circuit, plug connectors for connecting the units together, each said oscillator circuit including at least an anode electrode and a cathode electrode operating as space discharge means, means for connecting the cathode electrode of each oscillator circuit to a point of reference potential, each said amplifier circuit including at least a cathode element and an anode element operating as space discharge means, first switch means for connecting the anode electrode of the oscillator circuit of a selected one of said units with the cathode electrodes of the amplifier circuits of all of said units and thereby exciting the said cathodes at radio frequency potential above said reference point, and second switch means for connecting

the anode electrodes of the amplifier circuit of all of said units in circuit relation with the output circuit of said selected one of said units and the antenna and thereby exciting the output circuit of said selected one of said units and the antenna from all of said amplifier circuits.

7. A radio frequency transmitting system comprising an antenna, a plurality of transmitter units each comprising an oscillator circuit, an amplifier circuit and an output circuit, each said oscillator circuit including output means, each said amplifier circuit including at least a cathode element and an anode element operating as space discharge means, first switch means for connecting the output means of a selected one of said units with the cathode electrodes of the amplifier circuits of all of said units and thereby exciting the said cathodes from said output means, and second switch means for connecting the anode electrodes of the amplifier circuit of all of said units in circuit relation with the output circuit of said selected one of said units and the antenna and thereby exciting the output circuit of said selected one of said units and the antenna from all of said amplifier circuits.
